Att'y.

UNITED STATES PATENT OFFICE.

GEORGE E. STEVENS, OF LYNN, MASSACHUSETTS, ASSIGNOR TO GENERAL ELECTRIC COMPANY, A CORPORATION OF NEW YORK.

STARTING AND LIGHTING SET FOR AUTOMOBILES.

1,246,674.

Specification of Letters Patent.

Patented Nov. 13, 1917.

Application filed January 2, 1917. Serial No. 140,059.

To all whom it may concern:

Be it known that I, GEORGE E. STEVENS, a citizen of the United States, residing at Lynn, county of Essex, in the State of Massachusetts, have invented certain new and useful Improvements in Starting and Lighting Sets for Automobiles, of which the following is a specification.

The present invention relates to starting and lighting sets for automobiles, and particularly to those intended for Ford machines and in which the drive between the dynamo electric machine and the engine crank shaft is through a pair of directly meshing gear wheels. With such equipments a gear wheel is fastened directly on the end of the crank shaft of the engine. Meshing with this is a pinion carried by a shaft which is driven from the dynamo electric machine, which machine is suitably fastened to the engine frame. In installing such equipments difficulty is sometimes experienced in getting the parts alined so that the pinion and gear wheel mesh properly. This may be due, among other things, to irregularities in the surfaces upon which the parts are mounted.

The object of the present invention is to provide an improved structure in an equipment of this character, and particularly an improved coupling or connection between the pinion and the driving shaft which will allow them to be somewhat out of alinement with each other, and which will permit the pinion to adjust itself so as to mesh correctly with the gear wheel.

For a consideration of what I believe to be novel and my invention, attention is directed to the following specification, and the claims appended thereto.

In the drawings, Figure 1 is a side elevation of an internal combustion engine with the dynamo electric machine of a starting and lighting set mounted thereon, the engine being indicated in outline by dot and dash lines; Fig. 2 is a plan view of the coupling between the pinion and the driving shaft, the middle portion of the shaft being broken away; Fig. 3 is a section of the coupling of Fig. 2 on a larger scale; Fig. 4 is a section taken on line 4-4, Fig. 3, and Fig. 5 is a top view of a portion of the coupling, the end cap being shown in section.

Referring to the drawing, 10 indicates an internal combustion engine which may be

the engine of an automobile, and 11 a dynamo electric machine suitably supported thereon by a bracket 12 which carries a strap 13 surrounding its casing. These parts may be of any suitable structure so as to firmly support the dynamo electric machine. 14 indicates the armature shaft of the dynamo electric machine, and 15 a driving shaft to which is connected the pinion 16. The pinion 16 meshes with a gear wheel 17 mounted on the end of the crank shaft of the engine. As is well understood, the dynamo electric machine may be used as a motor to start the engine, after which the engine will drive it as a generator which may be utilized to charge a storage battery, etc.

Driving shaft 15 is connected to the armature shaft 14 by a coupling comprising two flexible plates 18 and 19, for example leather plates, suitably fastened to each other. The plate 18 is fastened to the armature shaft 14 in a suitable manner as by a member 20 fastened to the center of the plate and to the shaft end. The plate 19 is connected to the shaft 15 by means forming a slidable connection, and comprising a projecting tube 21 formed integral with a member 21^a similar to member 20 but extending at right angles thereto. The member 21^a is suitably fastened to plate 19. The tube 21 is provided with an angular opening into which the angular shaped end 22 of shaft 15 projects. This connection permits the shafts 14 and 15 to move axially relative to each other, and also angularly to a certain extent due to the flexibility of the plates 18 and 19.

Referring now particularly to Figs. 3, 4 and 5 in which the details of the connection between shaft 15 and the pinion 16 are shown, 23 indicates a spherical ball or head in which the end of shaft 15 terminates, and 24 a thread cut on the shaft 15 at a point spaced from the ball 23. In the ball 23 is an opening in which is fastened a pin 25 having its projecting ends provided with at least two flat sides, as indicated at 26. The pinion 16 may be of any suitable type, but is preferably of the so termed "noiseless" type, and is shown as comprising a body 27 of some compressible material, as spinnable textile fabric, held on a hub 28 between two end plates or shrouds 29 and 30. The hub 28 projects beyond the shroud 29, as indicated at 31. The shroud 30 has an integral projecting sleeve 32 threaded

on the outside to receive a cap 33. The sleeve 32 forms in substance a part of the hub 28, being integral with it as well as the shroud 30. The inner end of the sleeve 32 is formed with a spherical seat 34 against which rests the ball 23. On diametrically opposite sides, the sleeve 32 is provided with rectangular slots 35 which receive the ends of pin 25. 36 indicates a bracket which is 5 suitably fastened to the engine frame, as indicated at 27, 38 and 39, thus forming a three-point suspension. It comprises a body portion 40 having an opening 40^a, and a projecting sleeve 41 which slips into the hub 28, the end of the projecting portion 31 of the hub engaging a shoulder 42 on the body portion. The shaft 15 extends through the opening 40^a in the body portion 40 and the sleeve 41. The end of sleeve 41 engages the 10 ball 23, such end being suitably curved to form a continuation of the spherical seat 34. On the body portion 40 of bracket 36 is a spherical surface 43 having its center of curvature located at the center of the ball 23, and engaging the spherical surface 43 is a curved washer 44 splined to the shaft 15, as indicated at 45, to turn therewith, and held in place by lock nuts 46 screwed on the thread 24, there being a suitable bearing 15 washer 47, as a fiber or brass washer, between the surface 43 and the surface of the washer 44. As is clear from Fig. 3, the shaft 15 is of lesser diameter than the opening 40^a in body portion 40 and the opening 20 through sleeve 41, so that the shaft may take an angular position relative to the axis of the pinion 16. 48 indicates an oil cup and 25 49 an oil groove for conveying lubricant between the inner surface of the hub 28 and the outer surface of sleeve 41.

When the shaft 15 is rotated by the dynamo electric machine 11, it drives the pinion 16 through the connection comprising pin 25, the ends of which engage the two slots 35. The hub 28 of the pinion 16 rotates on the sleeve 41 which forms a bearing for it. The washer 44 also turns with shaft 15, bearing on the spherical surface 43.

When the parts are assembled it will be 30 seen that the pin 25 cannot come out as the shoulders formed at the base of the flat sides 26 on the ends of the pin engage the inner surface of the sleeve 32 adjacent the slots 35. This is clearly indicated by the 35 dotted lines in Fig. 5. As is clear from Fig. 3, the pinion 16 is held between the ball 23 and the shoulder 42, the parts being retained in position by the lock nuts 46 which hold the washer 44 up against spherical 40 surface 43. When the parts are clamped in position, the ends of the pin 25 are spaced somewhat from the bottom of the slots 35, as indicated on the drawing, so as to permit the shaft 15 to tilt in the plane common 45 to the axis of the pin 25 and shaft 15.

By the arrangement described, a universal connection is provided between the pinion 16 and the shaft 15. The shaft may move in one plane on pin 25 and in a plane at right angles thereto by pin 25 tilting in slots 35, 70 the ball 23 moving on spherical seat 34 and the curved washer 44 on spherical surface 43. Such a movement does not disturb the bearing seat between the surface 43 and the washer 44, as this surface has the same center as the ball 23 and spherical seat 34. This permits the shaft 15 to take a position at an angle to the axis of the pinion and to thereby assume a different axis of rotation 75 from that of the pinion. The pinion 16 can, therefore, within reasonable limits, always assume a position where it meshes correctly with gear wheel 17. At the same time the connection is a strong one, having no parts which are liable to work loose. 80

In accordance with the provisions of the patent statutes, I have described the principle of operation of my invention, together with the apparatus which I now consider to represent the best embodiment thereof; 90 but I desire to have it understood that the apparatus shown is only illustrative, and that the invention can be carried out by other means.

What I claim as new and desire to obtain 95 by Letters Patent of the United States is:

1. The combination with an internal combustion engine having a gear wheel on its crank shaft, of a dynamo electric machine supported adjacent the engine, a shaft connected to the rotor of the machine, a gear wheel which meshes with the first named gear wheel, a stationary cylindrical bearing upon which the second gear wheel rotates, said shaft extending loosely through said bearing and having a bearing surface which engages therewith, and means forming a universal connection between said shaft and the second named gear wheel. 105

2. The combination with an internal combustion engine having a gear wheel on its crank shaft, of a dynamo electric machine supported adjacent the engine, a shaft connected to the rotor of the machine by a flexible axially adjustable coupling, a gear 110 wheel which meshes with the first named gear wheel, and means forming a universal connection between the second named gear wheel and said shaft. 115

3. The combination with an internal combustion engine having a gear wheel on its crank shaft, of a dynamo electric machine supported adjacent the engine, a shaft connected to the rotor of the machine, a gear wheel which meshes with the first named gear wheel, and means forming a universal connection between the second named gear wheel and said shaft, said connection comprising a stationary sleeve upon which the second named gear wheel rotates, said shaft 125 130

extending through the sleeve and having a spherical surface on its end which engages a similar surface on the gear wheel, and means including a pin fastened to the end 5 of the shaft and engaging slots in the gear wheel for connecting the shaft to the gear wheel.

4. The combination with a shaft, of a gear wheel, and means for connecting it to the 10 shaft, comprising a stationary sleeve upon which the gear wheel turns, said sleeve having a greater diameter than the shaft and surrounding the same, a member having a spherical surface fixed to the shaft, said 15 surface engaging the end of the sleeve, and a pin which passes through the shaft, said gear wheel being provided with elongated slots with which the ends of the pin engage.

5. The combination with a shaft, of a gear 20 wheel, and means for connecting it to the shaft, comprising a stationary sleeve upon which the gear wheel turns, said sleeve having a greater diameter than the shaft and surrounding the same, a member having a 25 spherical surface fixed to the shaft, one end of the hub of said gear wheel and the end of said sleeve being provided with a spherical surface with which the spherical surface of said member engages, a shoulder on the 30 sleeve with which the other end of the gear

wheel hub engages, means for holding the gear wheel between the member on the end of the shaft and said shoulder, and a pin which extends through the end of the shaft, 35 said gear wheel having elongated slots with which the ends of the pin engage.

6. The combination with a shaft, of a gear wheel, and means for connecting it to the shaft, comprising a stationary member having an axial bore through which the shaft 40 extends, a bearing surface which passes inside the gear wheel, a shoulder on said member against which one end of the gear wheel rests, a head on the shaft having a spherical surface, the end of the gear wheel being provided with a similar spherical surface forming a seat for said head, a pin which passes through the shaft, said gear wheel being provided with slots with which the ends of the 45 pin engage, and means for holding the gear 50 wheel between said head and said shoulder comprising a part carried by the shaft and having a spherical surface which engages a similar surface on said member, said last named surfaces having a center of curvature 55 coinciding with that of the spherical surface on said head.

In witness whereof, I have hereunto set my hand this 29th day of December 1916.

GEORGE E. STEVENS.
